(57) **CLAIM**

The ornamental design for a three closure dispensing cap for a container, as shown and described.

DESCRIPTION

FIG. 1 is a perspective view of a dispensing cap showing a first embodiment of my new design, shown with the closures in the closed position;

FIG. 2 is a top plan view of the dispensing cap of FIG. 1; FIG. 3 is a perspective view of the dispensing cap of FIG. 1 shown with the closures in an open position;

FIG. 4 is a perspective view of a dispensing cap showing a second embodiment of my new design, shown with the closures in the closed position;

FIG. 5 is a top plan view of the dispensing cap of FIG. 4; and,

FIG. 6 is a perspective view of the dispensing cap of FIG. 4.

The broken line showing of the array of circles in the rectangular closure in FIGS. 1-3, the circles underneath the small rectangular closure in FIG. 3, and the remainder of the container body is for illustrative purposes only and forms no part of the claimed design.
